MASKED HELMET

Jack F. Furrer, Wayland, and Abraham L. Lastnik, Framingham, Mass., and Marvin A. Jarvis, Midland, Mich., assignors to the United States of America as represented by the Secretary of the Army

Application March 29, 1957, Serial No. 45,507

Term of patent 14 years

(Cl. D3—13)

(Granted under Title 35, U. S. Code (1952), sec. 266)

We claim:

The ornamental design for a masked helmet, substantially as shown.
